DESIGN FOR A FORK OR ANALOGOUS
ARTICLE

Harold E. Nock, Newburyport, Mass., assignor to
Towle Manufacturing Company, Newburyport,
Mass., a corporation of Massachusetts

Application April 4, 1939, Serial No. 84,031

Term of patent 14 years

To all whom it may concern:

Be it known that I, Harold E. Nock, a citizen of the United States residing at Newburyport, in the county of Essex and Commonwealth of Massachusetts, have invented a new, original, and ornamental Design for a Fork or Analogous Article, of which the following is a specification, reference being had to the accompanying drawing, forming a part thereof.

In the accompanying drawing, Figures 1 and 2 are front and back elevational views, respectively, of a fork showing my new design; Figs. 3, 4 and 5 are cross-sectional views taken on the lines 3—3, 4—4 and 5—5, respectively, of the handle shown in Fig. 1; and Fig. 6 is a fragmentary elevational

view on an enlarged scale of the upper portion of the handle shown in Fig. 1, for the purpose of more clearly bringing out the details of ornamentation.

The essential features of my design reside in the parts shown in full lines.

My design is delineated as embodied in the handle of a fork but my design may also be embodied in or applied to other handles of like nature.

I claim:

The ornamental design for a fork or analogous article, substantially as shown and described.

HAROLD E. NOCK.
